Chicago, Ill., a corporation of Delaware

Application March 15, 1950, Serial No. 8,536

Term of patent 14 years

(Cl. D26—7)

To all whom it may concern:

Be it known that we, Charles E. Jones and Robert H. Crowle, citizens of the United States, residing at Chicago and Berwyn, respectively, in the county of Cook and State of Illinois, have invented a new, original, and ornamental Design for a Fan Casing, of which the following is a specification, reference being had to the accompanying drawing, forming a part hereof.

In the drawing:

Fig. 1 is an elevation of a fan casing showing our new design;

Fig. 2 is an elevation at approximately 90 degrees from that shown in Fig. 1; and

Fig. 3 is a plan view.

The essential features of our design reside in the portions shown in full lines.

We claim:

The ornamental design for a fan casing, substantially as shown and described.

CHARLES E. JONES.

ROBERT H. CROWLE.
